UNITED STATES PATENT OFFICE.

ERNEST JOHN, OF ARDMORE, PENNSYLVANIA.

BOOK AND METHOD OF BINDING THE SAME.

Application filed December 28, 1922. Serial No. 609,502.

To all whom it may concern:

Be it known that I, ERNEST JOHN, a subject of the King of Great Britain, a resident of Ardmore, in the county of Montgomery and State of Pennsylvania, have invented a certain new and useful Book and Method of Binding the Same, of which the following is a specification.

This invention relates to improvements in books and method of binding the same and the principal object is the provision of a loose leaf book construction which may be readily assembled so that when the book is opened and the pages turned each page or leaf will lie flat without bending, bulging, or wrinkling and will not recoil or spring back when once turned over.

A further object of this invention is the provision of a book construction composed of a plurality of pages or leaves, each of which is bent, folded, or creased to form a page proper and a back part, the pages or leaves being arranged in a plurality of groups and having a loose hinge and holding member connecting the groups together, the back portions of the leaves being loose and free to move whereby when the book is opened, the pages will lie flat and will not bulge or bend and will not recoil or spring back when once turned over.

Another object of this invention is the provision of a book construction composed of a plurality of separate pages or leaves each arranged to form a page proper and a back part and positioned in a plurality of separate groups with means for loosely holding the groups in associated relation, the individual pages or leaves not being connected together, so that any one may be removed and a new one substituted if desired without disturbing the book structure as a whole, each page or leaf having the necessary freedom of action so that it may adjust itself to the various angles assumed in opening and closing the book.

A further object of this invention is the provision of such a book construction having combined hinge and holding members with parts arranged between the folded portions of the leaves, said parts offering no resistance or obstruction to the turning of the leaves and providing means whereby said members may turn upon themselves with the result that the pages, when opened,

will lie flat and not bulge or bend or recoil or spring back.

Another object of this invention is the method of binding, which includes providing a plurality of separate leaves bent, folded, or creased to provide a page portion and a back portion, and arranged in opposed groups, and a loose member which combines the function of a hinge and holding member loosely connecting the leaves of the two groups together, the back portions of the leaves fitting within a suitable holder or cover part and being loose therein, whereby when the book is bent and the pages are turned, the pages will lie flat and will not bend, bulge or wrinkle, and will not recoil or spring back when once turned over.

To the accomplishment of the foregoing and such other objects as may hereinafter appear, my invention consists in the construction, arrangement, and combination of parts hereinafter described, as well as the method hereinafter described, reference being had to the accompanying drawings which show two forms of my invention, it being expressly understood, however, that various changes may be made in practice within the scope of the claims without departing from my inventive idea.

In the drawings,—

Figure 1 represents a perspective view of a book constructed according to my invention shown in open position at the division between the two groups of leaves.

Figure 2 is a longitudinal section across one entire part of the book and the hinge portion of the other part of the book showing the manner of holding the combined hinge and holding members in position and also the assembling of the groups of leaves within the back of the book.

Figure 3 is a longitudinal section through part of the book shown in Figure 1, the combined hinge and holding member being shown in elevation and the book being open at the division between the two groups of leaves.

Figure 4 is a similar view showing the pages unequally divided.

Figure 5 is another similar view showing all the pages but one turned to one side.

Figure 6 is a view similar to Figure 3 of a slightly modified form wherein a stiff back member is provided and the back portions of

the leaves merely fit therein and do not extend to the outer edge thereof because they do not form the back portions themselves.

Figure 7 is a perspective view of one of the combined hinge and holding members.

This invention is designed particularly for catalog and display books which are usually printed on rather heavy paper of various kinds and which are expensive and are inefficiently bound, resulting in the bending, bulging and wrinkling of the pages when the book is opened and in which the pages recoil or spring back when turned over and also having no provision for the substitution of sheets in the event it become necessary or desirable to make changes in the book as a whole.

It is to overcome these as well as other disadvantages that my invention is designed, and, in addition, provision is made for the use of a varying number of sheets according to necessity and desire.

Referring now to the drawings, the numeral 10 designates one of the leaves, a plurality of which are used to form the book. Each leaf 10 has the page part 11, and is folded, bent, or creased at 12 to provide a back part or portion 13. The leaves are preferably assembled in a plurality of groups, two groups being illustrated and arranged with their bent portions opposed, and a combined hinge and holding member 14 is inserted between the folded portions of the two groups of leaves. This member preferably takes the form of an elongated U-shaped clip having the elongated legs 15 and the looped portion 16, the latter appearing at the outside edge of the leaves. The legs 15 extend inwardly in the folded portions of the leaves a sufficient distance to form suitable hinging and holding means and may be relatively long or short as desired. The legs 15 are round and this is important in that the members 14 are free to turn upon themselves within the leaves. This combined hinging and holding member 14 is suitably held by means of the anchoring member 17. This is in the form of a folded piece of paper or suitable fabric having a suitable reinforcing member 18 of fabric or other material bent so as to fold rather tightly around the legs 15 of the combined hinge and holding member 14. The purpose of the anchoring member 17 is to hold the combined hinge and holding members 14 in position and prevent the same from skewing or twisting out of position and offering resistance to the turning of the pages which would result in the disadvantages above referred to. These members 14 are free to turn on one of the legs 15 as a center, depending upon which group of leaves is thrown over, as shown in Figures 3, 4 and 5 of the drawing, this form of loose connection being an important consideration. The

anchoring member also prevents the hinging and holding members 14 from wearing or breaking through the leaves, it being understood that the latter are loosely held in position thereby and may be readily withdrawn at any time.

In the embodiment of my invention illustrated in Figures 2 to 5, inclusive, the back parts or portions 13 of the leaves are sufficient in size to extend substantially the full width of the cover 19. They fit therein, extending to the edge of the cover, and by their own body form a stiff back for the book. A slight variation of this is illustrated in Figure 6 where a stiff back 20 is provided and where the back parts or portions 13' of the leaves are shorter and do not extend to the extreme edge of the back 20. A filler 21 of suitable material may be used in remaining space, if desired.

It is to be noted that I have also provided a filler member for book constructions which may be utilized with backs or covers of various kinds, this filler construction including a plurality of leaves folded to provide page portions and back parts and arranged in groups with folded portions of the groups positioned in opposed relation and having means for holding the groups together in hinged relation.

It is to be noted that the leaves are not connected together or to the combined hinging and holding members at any point whatsoever. The page parts are loose and free to move one upon another. The back parts or portions are loose and free to move one upon another, and the bent, folded, or creased portions at and adjacent the hinge are also loose and free to move one upon the other. This is very important in that it permits the necessary freedom of action between each leaf or group of leaves so that they may adjust themselves to the various angles assumed by the parts in opening and closing the book and in turning the pages. Further, the combined hinging and holding members are loosely held in position and are free to turn upon themselves, the legs lying loosely within the folds of the leaves and not offering any resistance or obstruction to the turning thereof. All of these points are illustrated and brought out clearly in Figures 3, 4 and 5 of the drawing. The pages will always lie flat when open, and individual pages may be readily withdrawn and substitutions made without disturbing the remainder of the leaves or pages in any way.

What I claim is:—

1. The method of binding a plurality of loose leaves so that any one may be removed and so that the page portions thereof will lie flat without bending or wrinkling or recoil or springing back when opened, including the provision of a back or cover

having pockets, folding each leaf so that it will have a page part and a back part, arranging the leaves in groups with the folded portions of the leaves opposed and with their back parts positioned within the pockets of the cover, and loosely connecting the groups together in a hinged relation.

2. The method of binding a plurality of loose leaves so that any one may be removed and so that the page portions thereof will lie flat without bending or wrinkling or recoiling or springing back when opened, including the provision of a back or cover having pockets, folding each leaf so that it will have a page part and a back part, arranging the leaves in groups with the folded portions of the leaves opposed and with their back parts positioned within the pockets of the cover, and connecting said groups together loosely by means having parts extending into said folded portions and arranged so as to offer no resistance or obstruction to the turning of the leaves.

3. The method of binding a plurality of loose leaves so that any one may be removed and so that the page portions thereof will lie flat without bending or wrinkling or recoiling or springing back when opened, including the provision of a back or cover having pockets, folding each leaf so that it will have a page part and a back part, arranging the leaves in groups with the folded portions of the leaves opposed and with their back parts positioned within the pockets of the cover, and providing a connecting medium for said groups of leaves with parts thereof extending within the folded portions of each group, whereby the groups are associated in hinged relation.

4. The method of binding a plurality of loose leaves so that any one may be removed and so that the page portions thereof will lie flat without bending or wrinkling or recoiling or springing back when opened, including the provision of a back or cover having pockets, folding each leaf so that it will have a page part and a back part, arranging the leaves in groups with the folded portions of the leaves opposed and with their back parts positioned within the pockets of the cover, and providing a hinged connection between said group of leaves which is loose and offers no resistance or obstruction to the turning of the leaves.

5. The method of binding books which includes the provision of a back or cover having two pockets and a plurality of separate leaves, folding each leaf to provide a page part and a back part, arranging the leaves in groups having their folded portions opposed and with their back parts positioned within the pockets of the cover, and loosely connecting the groups of leaves together in a hinged relation.

6. The method of binding books which in-

cludes the provision of a back or cover having two pockets and a plurality of separate leaves, folding each leaf to provide a page part and a back part, arranging the leaves in groups having their folded portions opposed and with their back parts positioned within the pockets of the cover, and hinging the groups together by means extending outside the edges of the leaves so as not to interfere with the removal of individual leaves.

7. A book including a plurality of leaves, each leaf being folded to provide a page part and a back part, the leaves being arranged in groups with the folded portions of each group positioned in opposed relation, and a combined hinge and holding member for loosely holding the groups in associated and hinged relation.

8. A book including a plurality of leaves, each leaf being folded to provide a page part and a back part, the leaves being arranged in groups with the folded portions of each group being positioned in opposed relation, and a combined hinge and holding member for loosely holding the groups in associated and hinged relation and having parts positioned within the folded portions of each group, said parts being loose so that said member is free to turn upon itself without offering resistance or obstruction to the turning of the leaves.

9. A book including a cover having a plurality of pockets therein, a plurality of separate leaves, each leaf being folded to provide a page part and a back part, the leaves being arranged in groups and the folded portions of each group being positioned in opposed relation, the back part of the leaves of each group being positioned within a pocket of the cover, and a combined hinge and holding member loosely positioned within the folded portions of each group of leaves for loosely holding the groups in a hinged and associated relation.

10. A book, including, in combination, a back or cover having pockets therein, a plurality of leaves folded to provide page parts and back parts, said leaves being arranged in groups with their folded portions in opposed relation and with their back parts loosely fitting within the pockets in the cover, and a combined hinge and holding member for loosely holding the groups of leaves in hinged and associated relation.

11. A book including, in combination, a back or cover having pockets therein, a plurality of leaves folded to provide page parts and back parts, said leaves being arranged in groups with their folded portions in opposed relation and with their back parts loosely fitting within the pockets in the cover, and a combined hinge and holding member for loosely holding the groups of leaves in hinged and associated relation,

4

said last-mentioned member having a part positioned within the folded portion of each group of leaves and also having a connecting medium between said parts, said connecting medium being positioned without the edges of said leaves whereby individual leaves may be withdrawn without interfering with the remainder of the book structure.

12. A filler for a book back, including, a plurality of separate leaves, each leaf being folded to provide a page part and a back part, the leaves being arranged in groups with the back parts extending in opposite directions and with the folded portions of each group positioned in opposed relation, and means for loosely holding the groups in a hinged and associated relation.

13. A filler for a book back, including, a plurality of separate leaves, each leaf being folded to provide a page part and a back part, the leaves being arranged in groups with the back parts extending in opposite directions and with the folded portions of each group positioned in opposed relation, and a single means for loosely holding the groups in a hinged and associated relation.

14. A filler for a book back, including, a plurality of separate leaves, each leaf being folded to provide a page part and a back

part, the leaves being arranged in groups with the back parts extending in opposite directions and with the folded portions of each group positioned in opposed relation, and a combined hinge and holding member having a part positioned within the folded portion of each group of leaves and having a connecting medium therefor whereby the leaves are held in hinged and associated relation.

15. A filler for a book back, including, a plurality of separate leaves, each leaf being folded to provide a page part and a back part, the leaves being arranged in groups with the back parts extending in opposite directions and with the folded portions of each group being positioned in opposed relation, and a combined hinge and holding member having parts adapted to be positioned within the folded portions of each group of leaves and having a connecting medium therefor positioned beyond the edges of said leaves whereby the groups of leaves are held in hinged and associated relation and individual leaves may be withdrawn from each group of leaves.

In testimony that I claim the foregoing, I have hereunto set my hand this 12th day of December, 1922.

ERNEST JOHN.
